C. E. DANIELS.
PORTABLE CLEANING DEVICE.
APPLICATION FILED MAR. 27, 1915.

1,187,819.

Patented June 20, 1916.

UNITED STATES PATENT OFFICE.

CHARLES EDWARD DANIELS, OF ATCHISON, KANSAS.

PORTABLE CLEANING DEVICE.

1,187,819.

Specification of Letters Patent. Patented June 20, 1916.

Application filed March 27, 1915. Serial No. 17,471.

To all whom it may concern:

Be it known that I, CHARLES E. DANIELS, a citizen of the United States, residing at Atchison, in the county of Atchison and State of Kansas, have invented certain new and useful Improvements in Portable Cleaning Devices, of which the following is a specification.

This invention relates generally to cleaning apparatus, and more especially to a portable device for discharging a liquid detergent under pressure which renders the same particularly useful for removing grease, oil, and the like from automobile and other engine parts.

It is particularly desirable in repairing parts of motor car engines and like surfaces which may be coated with grease, oil, and dirt, that the same be cleaned easily and quickly without dismantling the entire mechanism and placing the individual pieces in a bath of gasoline or similar cleaning liquid. Furthermore, it is not always convenient or practicable to remove the grease with cotton waste or otherwise displace the same by a scraping tool. Therefore, the present invention contemplates a novel portable container or vessel for a cleaning liquid, such as gasoline, coal oil, or the like, which may be connected with a suitable source of compressed air supply to force the detergent agent onto the surface or article to be cleaned through a conveniently manipulated hand nozzle.

To this end, the invention contemplates a substantial and practical construction of container or tank having a novel arrangement of air and liquid controlling valves which may be easily and quickly manipulated and minutely adjusted to regulate the supply of cleaning fluid forced from the container.

While the invention is primarily intended for use in cleaning operations, it may be also provided with suitable instrumentalities whereby it may be readily converted and used as a blow torch.

With the above and other objects in view which will more readily appear as the nature of the invention is better understood, the same consists in the novel construction, combination and arrangement of parts hereinafter more fully described, illustrated and claimed.

A preferred and practical embodiment of

the invention is illustrated in the accompanying drawings, in which—

Figure 1 is a perspective view of the invention showing the novel valve arrangement and brush nozzle. Fig. 2 is an enlarged detail sectional view showing the interior construction of the tank and valve device. Fig. 3 is a detail sectional view of the discharge nozzle.

Similar reference characters designate corresponding parts throughout the several figures of the drawings.

In the embodiment of the invention disclosed in the drawings, the same essentially comprises a suitable container or tank 1 which may be of any convenient form or size and preferably provided at its lower end with a base support 2 for permitting the same to stand on end when in operative position. To facilitate the handling and portability of the tank, there may be provided a swinging bail or handle 3, and also to enable the tank to be filled with the cleaning liquid or fluid, the same is provided with a suitable filler spout 4 having a closure plug 5.

Detachably fitted in the head 6 of the tank is a combination air intake and liquid discharge valve device designated generally by the reference letter V, and comprising a hollow valve casing 7 formed with a central cap portion 8 and the oppositely disposed nipple extensions 9 and 10. The casing 7 also includes a hollow shank portion 11 which may be provided with suitable threads 12 to enable the same to be screwed into the head of the tank, thus facilitating the fitting and removal of the entire valve device from the tank when repairs thereto are necessary. The greater portion of the shank 11 extends down into the interior of the tank 1 and has a plurality of air ports 13, thus establishing communication between the interior of the valve casing and the interior of the tank.

Arranged within the valve casing 7 and extending through and beyond the shank portion 11 is a liquid supply pipe 14 which is of less diameter than the shank 11 thus providing an annular air space or chamber 11a between the walls of the shank and the exterior of the liquid pipe. This liquid pipe 14 is preferably threaded at its upper end as at 15 so that it may be screwed into the central cap portion 8 of the valve casing, 110

and has its lower end 16 in close proximity to the bottom of the tank 1. For the purpose of properly centering and positioning the siphon pipe 14 within the shank 11, the latter is provided at its lower end with a suitable screw plug bushing 17. In addition to being exteriorly threaded at its upper end to be screwed in the central cap portion 8 of the valve casing, the pipe 14 is interiorly threaded to provide for receiving the threaded stem 18 of a liquid supply-regulating turn plug 19 which is adapted to control a port 20 in the pipe 14 which is in communication with a laterally disposed liquid delivery tube 21 extending into the nipple extension 10.

In connection with the oppositely disposed nipple extensions 9 and 10 of the valve casing it will be observed that the former has fitted thereto an air intake valve 22 while the latter has fitted thereto a similar type of outlet or discharge valve 23. These valves 22 and 23 when fitted to the valve casing as above explained coöperate therewith to provide an air pressure receiving chamber 24 and a delivery chamber 25 which are in direct communication with each other and also in communication with the annular chamber 11^a.

In use the tank or container 1 is fitted with a suitable cleaning liquid, gasoline, coal oil, or other fluid capable of removing grease, and the valve 22 is connected by means of a hose or tube to a source of compressed air supply. When the plug of this valve is opened, air will enter the chamber 24 and pass down into the annular chamber 11^a and out of the ports 13 thus forcing the liquid up through the pipe 14 and also through the delivery tube 21, and into the chamber 25 where it is ejected or forced out through the discharge valve 23 into suitable means for applying the liquid to the parts to be sprayed and cleaned, such for instance as a flexible hose 26 having thereon a hand nozzle designated in its entirety by the reference 27. This hand nozzle 27 preferably includes a hand grip 28 and a stem 29 having at its open end a detachable discharge nozzle 30 which is preferably provided with a wire brush or equivalent element for augmenting the cleaning operation.

From the foregoing description, it will be apparent that the novel valve device makes special provision for supplying a cleaning liquid to a hand nozzle under pressure, the volume of which liquid can at all times be easily regulated independent of a constant air pressure supply. In fact, where the occasion demands, the liquid supply can be entirely cut off and the hand nozzle discharge only air or practically a solid stream of liquid may be discharged. Furthermore, this valve arrangement gives the present de-

vice another utility, namely, that of a blow torch, and to provide for this adaptation of the device, the tank 1 has arranged therein a blow tube 32, the exposed end of which is normally covered during the use of the device as a cleaner by a blank plug or cap 33. However, this plug may be easily removed and any standard type of torch burner inserted in its place.

When the device is used as a blow torch the valve 23 is closed, and the port 20 of the tube 14 is also closed, and the blow torch element inserted in the end of the tube 32. The valve 22 is then opened and put in communication with a compressed air supply, and the compressed air allowed to fill the tank to capacity. The valve 22 is then closed thus holding the liquid under pressure and rendering the device capable of discharging the usual igniting fluid for the torch.

Without further description, it is thought that the many features and advantages of the invention will be readily apparent, and it will of course be understood that various changes in the form, proportion and minor details of construction may be resorted to without departing from the spirit of the invention or scope of the appended claims.

I claim:

1. A device of the class described including a tank, a valve device fitted to said tank and including a casing having oppositely disposed nipple extensions provided with intake and discharge valves, and also provided with a hollow depending shank portion having a plurality of outlet ports, a liquid supply pipe arranged within the hollow shank, an off-set tube carried by said supply pipe and discharging into the nipple extension having the discharge valve, a valve for controlling said tube, and a delivery nozzle in piped communication with said discharge valve.

2. A device of the class described including a tank, a valve device fitted to said tank and including a casing having oppositely disposed communicating nipple extensions provided with intake and discharge valves, and also provided with a hollow depending shank portion having outlet ports, a sealing plug detachably fitted into the end of said shank portion and having an opening, a liquid supply pipe fitted in said opening of the sealing plug and having a portion thereof arranged within the hollow shank, a laterally off-set tube carried by said supply pipe and discharging into the nipple extension having a discharge valve, a valve for controlling said tube, and a delivery nozzle in piped communication with said discharge valve.

3. A device of the class described including a tank, a valve device fitted to said tank and including a casing having oppositely disposed nipple extensions and an interme-

diate hollow depending shank provided with outlet ports, an air pressure intake valve fitted to one of said nipple extensions and a liquid discharge valve fitted to the other of 5 said extensions, a liquid conveyer pipe arranged in said valve casing between said nipple extensions and extending down into the tank through said shank, a delivery tube carried by said liquid pipe and discharging 10 in said nipple extension having the liquid

discharge valve, a regulating valve for said delivery tube, and a delivery nozzle in piped communication with said discharge valve.

In testimony whereof I hereunto affix my signature in the presence of two witnesses. 15

CHARLES EDWARD DANIELS.
